UNITED STATES PATENT OFFICE.

WILLIAM M. GREEN, OF NEW YORK, N. Y.

DESIGN FOR A JARDINIÈRE.

SPECIFICATION forming part of Design No. 28,638, dated May 17, 1898.

Application filed April 7, 1898. Serial No. 676,829. Term of patent 3½ years.

To all whom it may concern:

Be it known that I, WILLIAM M. GREEN, a subject of the Queen of Great Britain, residing at the city of New York, (borough of Manhattan,) in the county of New York and State of New York, have invented and produced a new and original Design for a Jardinière, of which the following is a specification, reference being had to the accompanying drawing, forming a part thereof, in which is represented a perspective view of a jardinière embodying the features of my design.

The leading feature of the design consists in a semi-oval body comprising a top band A and a bottom drop ornament B, the band and bottom ornament being apparently connected

by a series of ribs and a bowl C, that is visible at the spaces between the ribs. The legs D have flat sides and are fitted to the exterior of the body, the legs being inwardly curved between their lower ends and the body and outwardly curved at their lower extremities. The body is decorated with festooned chains E and a platform is located between the legs. 25

I claim—

The design for a jardinière as herein shown and described.

WILLIAM M. GREEN.
